UNITED STATES PATENT OFFICE.

HENRY TRUESDELL, OF TORONTO, CANADA.

DESIGN FOR A GRATE-BAR.

SPECIFICATION forming part of Design No. 33,201, dated September 11, 1900.

Application filed March 2, 1900. Serial No. 7,136. Term of patent 14 years.

To all whom it may concern:

Be it known that I, HENRY TRUESDELL, a citizen of the United States, residing at 16 Camden street, in the city of Toronto, in the county of York and Province of Ontario, Canada, have invented and produced a new and original Design for Grate-Bars; and I hereby declare that the following is a full, clear, and exact description of the same, reference being had to the accompanying drawings, forming part thereof.

In the drawings, Figure 1 is a perspective view of the grate-bar. Fig. 2 is a longitudinal section through the same, and Fig. 3 is a transverse section of the grate-bar.

Like letters of reference refer to like parts throughout the specification and drawings.

As shown in the drawings, the leading feature of my design consists of a substantially-rectangular frame and a series of transverse sections connected to the rectangular frame, the top surfaces of which are provided with longitudinal grooves or corrugations extending from end to end of the grate-bar.

A represents the frame of the grate-bar, which consists of two opposite and parallel sides $a\ a$ and two ends $a'\ a'$. Each of the sides $a\ a$ is substantially truss-shaped, as shown in Fig. 1 of the drawings, and the top of each of the sides is provided with a longitudinal corrugation or groove a'' , extending from end to end of the same. Formed integrally with the sides $a\ a$ are a series of trans-

verse sections B, the tops of which are on the same plane and of the same shape as the top of the ends $a'\ a'$. Extending along the middle of the top of the sections B and ends $a'\ a'$ is a groove or corrugation C, and at each side of the groove or corrugation C is a groove or corrugation D. The grooves or corrugations D are intermediate the grooves or corrugations C and the grooves or corrugations $a''\ a''$. By reference to the drawings it will be noticed that the ends $a'\ a'$ and sections B project beyond the sides $a\ a$ of the frame and that the grooves or corrugations E extend along the top of the projecting ends $a'\ a'$ and sections B from end to end of the grate-bar. The sections B in cross-section, it will be noticed, are wedge-shaped, and connected to the outer face of each of the ends $a''\ a''$ is a mandrel F. Depending from one of the ends $a''\ a''$ is a lug G, having a hole H in its lower end.

Having described my invention, what I claim as new, and desire to secure by Letters Patent, is—

The design for a grate-bar herein shown and described.

In testimony whereof I have signed my name to this specification in the presence of two subscribing witnesses.

H. TRUESDELL.
